UNITED STATES PATENT OFFICE.

ANDERS GUSTAF HOLMBERG, OF LÄNGGRUVAN, SWEDEN.

MAGNETIC ORE-SEPARATOR.

972,109.

Specification of Letters Patent.

Patented Oct. 4, 1910.

Application filed November 27, 1908. Serial No. 464,757.

To all whom it may concern:

Be it known that I, ANDERS GUSTAF HOLMBERG, a subject of the King of Sweden, residing at Långgrufvan, in the Kingdom 5 of Sweden, have invented a new and useful Magnetic Ore-Separator, of which the following is a specification.

This invention refers to a magnetic ore separator, which has a trough, in which 10 the pulverized ore suspended in water and gangue is intended to be let in and a belt running in the trough, above which belt are some groups of electro-magnets for the purpose of attracting the particles of the ore 15 to the belt for separating these from the gangue and further transporting them toward an outlet and below the interspaces between of the groups, pits in the trough, which pits are furnished with tubes for the 20 purpose of partly washing away the particles of ore and possibly adhering particles of the gangue from the belt and partly suspending these particles in water, and also below each group of magnets a pit formed 25 in the trough and furnished with a tube in order to wash away the gangue, which possibly might be on the belt or on the particles of the ore, and each pit below the groups of 30 the magnets has a bottom sloping toward one side of the trough, at the lower edge of which bottom is an outlet for removing particles of gangue falling down. Such a magnetic ore separator is shown on the attached drawing where—

35 Figure 1 shows the same partially in longitudinal vertical section, Fig. 2 in cross section along the line *a*—*b* in Fig. 1 looking from the left with the tube 14 and the magnet 6 not in section and Fig. 3 in cross section along the line *c*—*d* in Fig. 1 also from the left and with the tube 10 not in section.

40 1 is the trough, into whose inlet end a sloping trough opens, while its outlet end joins another sloping trough 3.

45 4 indicates the belt, which is shown in the shape of an endless belt running over the pulleys 5 at the ends of the trough 1. The lower part of the belt forms as shown an interspace with the bottom of the trough, 50 whereby the above mentioned lower part runs either into or above the water.

55 6 indicates the electro-magnets, which in the case shown are divided in four successive groups I, II, III and IV. These magnets are placed a little above the lower part of

the belt 4, which conveniently runs on flanges 7 attached to the sides of the trough.

In the bottom of the trough is made a pit 8 in advance of each group of magnets. From the side of the trough 1 a tube 10 60 enters each pit 8 with the nozzle directed downward, which nozzle passes through a perforated plate 16 placed in the pit and ends in the space between this plate and the bottom of the pit. Through this tube 10 65 the water is forced into the space below the plate 16, which water passes up in fine jets through the many small holes in the plate 16 and effectually suspends in water the particles of ore, which have dropped from 70 the belt 4 and have run with the water down in the pits 8. The horizontal part of this tube 10 is furnished with openings placed in such a way, that jets directed obliquely upward hit the belt 4 for the purpose of 75 washing away the particles of ore and the particles of gangue, which possibly might have been brought along with the ore.

12 indicates the pits below the magnet groups. In these pits 12 washing tubes 14 80 enter for the purpose of washing away the gangue, that possibly might be on the belt or on the particles of the ore. The pits 12 have each a bottom 15 (Fig. 2) sloping toward one side of the trough, at the lower 85 edge of which bottom is an outlet 9 for the particles of the gangue dropped in the pits 12 or brought there by means of the water, which particles of gangue farther on are brought away in the trough 18. The projections 17 keep the particles of ore until the magnets have pulled these latter against the belt 4.

The finely pulverized mass of ore and gangue suspended in water is brought in 95 through the trough 2 into the trough 1 and is at the first pit 8 exposed to fine jets of water from the space below the perforated plate 16, which jets still more suspend the mass in water. When the stream of water 100 carrying the ore is brought farther below the first group of electro-magnets I, the particles of ore are attracted to the belt and pressed against it and carried forward by 105 the belt. It is however evident that some gangue also is caught on the belt and among the particles of ore. The tube 14 is intended for washing away this gangue. These particles of gangue so washed away, together with particles of the same kind, carried in 110

the trough sink or fall down in the pit 12 and are carried away through the opening 9 (Fig. 2) down in the discharge trough 18, but a part of the particles of gangue is entangled among the particles of attracted ore, wherefore a further separating is necessary. Between the groups of electro-magnets I and II, therefore another suspending in water is attained in the pit 8 partly of particles 10 dropped from the belt, because the magnetism now does not act on them, and partly of particles washed away from the belt by the tube 10 after which another attracting of the particles of ore is done below the group 15 of electro-magnets II. In the same way also the third and fourth groups of electro-magnets work, so that the ore at the shown separator is separated four consecutive times. After passing the last group IV, the last 20 tube 19 washes away the particles of ore from the belt down in the discharge trough 3.

I claim—

1. In a magnetic ore separator, an elongated trough, an endless belt therein spaced therefrom, a plurality of sets of magnets above the lower run of the belt, the trough being formed with a pit in advance of each group of magnets, a foraminated plate in each such pit, a water delivery tube for each 25 such pit having a nozzle projected downwardly through the foraminated plate and terminating in the space below said plate, the trough being also formed with a pit un- 30

der each group of magnets, each such pit having a transversely sloping bottom and 35 being provided with a discharge at the end of the bottom, and means for feeding material to the trough.

2. In a magnetic ore separator, an elongated trough, an endless belt therein spaced 40 therefrom, a plurality of sets of magnets above the lower run of the belt, the trough being formed with a pit in advance of each group of magnets, a foraminated plate in each such pit, a water delivery tube for each 45 such pit having a nozzle projected downwardly through the foraminated plate and terminating in the space below said plate, said tube having on its top surface a plurality of outlets directed toward the belt, the trough being also formed with a pit under 50 each group of magnets, each such pit having a transversely sloping bottom and being provided with a discharge at the end of the bottom, a water delivery tube for each pit under the groups of magnets, said tube having a plurality of outlets directed toward the belt, and means for feeding material to the 55 trough.

In testimony that I claim the foregoing as my invention, I have signed my name in presence of two subscribing witnesses.

ANDERS GUSTAF HOLMBERG.
